G. B. GALLASCH

DISPLAY APPARATUS

Filed July 15 1925

UNITED STATES PATENT OFFICE.

GEORGE B. GALLASCH, OF ROCHESTER, NEW YORK, ASSIGNOR TO BAUSCH & LOMB OPTICAL COMPANY, OF ROCHESTER, NEW YORK, A CORPORATION OF NEW YORK.

DISPLAY APPARATUS.

Application filed July 15, 1925. Serial No. 43,738.

The present invention relates to a display apparatus, and has for one object to provide improved means by which a normally invisible mark or markings on a transparent article may be rendered visible when desired.

More particularly the invention has for its object to provide an improved vaporizing device for supplying moisture to a lens or other polished glass or transparent article on which has been placed a normally invisible mark or markings, such as a trademark or the name of the maker of the goods which is so applied as to be quickly rendered visible by the application of moisture or vapor thereto.

A further object of the invention is to provide a combined vaporizing and illuminating device for displaying normally invisible markings of the articles, in which the illuminating means is preferably employed for vaporizing a suitable liquid in a container with which said illuminating means is associated.

To these and other ends the invention resides in certain improvements and combinations of parts, all as will be hereinafter more fully described, the novel features being pointed out in the claims at the end of the specification.

In the drawings:—

Figure 1 is a view in elevation of a device embodying the invention;

Figure 2 is a sectional elevation taken centrally through the container shown in Figure 1;

Figure 3 is a fragmentary sectional elevation through the base of the container taken at a right angle to the section shown in Figure 2, and

Figure 4 illustrates a lens showing a normally invisible mark as it appears when rendered visible upon the application of moisture thereto.

Similar reference numerals throughout the several views indicate the same parts.

The present invention is designed particularly for use in identifying the type, grade, name of maker, or other characteristics of transparent articles, such as ophthalmic lenses on which invisible markings have been placed by any suitable method, and which will be readily developed and rendered visible upon apply-

ing moisture thereto, produced from any suitable liquid, preferably from water.

Referring to the drawings, 10 represents a casing or container for holding a supply of liquid and the necessary means for evaporating the same. The container is preferably of a tapering construction having an enlarged base terminating in an annular flange 11 whereby it is prevented from being easily overturned. A pad 12 of relatively soft material is secured to the bottom of the container to prevent marring of the surfaces upon which the base is adapted to rest. The upper end of the container is preferably considerably reduced in diameter and is provided with a ring 13 of soft

rubber or other suitable material for receiving the article to be displayed, such as the ophthalmic lens indicated at 14, having any desired normally invisible mark or markings 15 on one of its surfaces, preferably the concave surface 16 thereof. The article is shown in display position in Figure 2 over an opening 17 of the ring 13 which is grooved to receive the inwardly extending flange 18 of the container. The container at this point is preferably inclined with respect to its vertical axis to facilitate viewing the article when the container is supported in elevated position, as when used on counters or show cases in stores handling optical goods of the character shown.

The container is provided with a liquid holding chamber 18 in which a supply of suitable liquid 19 is shown, preferably water. The container is provided with a spout 20 through which the liquid holding chamber is filled, the spout being preferably provided with a hinged cover 21 normally held tightly closed by a spring 22 in a well known manner.

The bottom of the liquid holding chamber comprises a transverse wall 23 spaced above the bottom of the container having an opening 24 through which is projected a tubular member 25 having an annular flange 26 preferably extended beneath the wall and forming therewith a liquid tight joint through the use of a suitable cement 26^a interposed between the flange and wall. The tubular member is supported by a clamping ring 27 secured to said transverse wall by screws 28 as shown in Figure 2.

A wick 29 surrounds the tubular member being extended preferably the full length of the latter with its lower end disposed within the liquid holding chamber.

5. A combined heating and illuminating element 30 is disposed within the tubular member for both supplying heat to vaporize the liquid absorbed by the wick and light for illuminating the moisture covered portion 10 of the article, whereby to render visible the normally invisible mark or markings 15 thereon. The heating element is preferably in the form of an electric lamp screwed into a socket 32 removably supported in the bottom of the container in any suitable manner, as by a yieldable bar 33, the opposite ends of which rest upon the upper faces of a pair of lugs or abutments 34 on the inner wall of the container. The 20 lamp and the socket, together with the bar 33, can be readily removed from the container as a unit by rotating the same until the ends of the bar are brought to a position at which they will clear the lugs 34. The 25 socket is provided with a lamp cord 35 for conveniently attaching the device to a current supply source, the cord being extended through a sleeve 36 in the lower wall of the container, as shown in Figure 3.
30. A suitable diaphragm plate 37 is interposed between the lamp and the lens-holding ring 13, the diaphragm being preferably formed integral with the tubular member 25, though it may be separate therefrom if desired. The diaphragm is provided with an aperture 38 of a somewhat restricted area for diminishing the amount of light projected upon the surface of the article containing the markings to be displayed whereby to avoid a blinding light, and in this connection the lamp is preferably of the frosted type to further reduce the degree of illumination.
45. The upper end of the bulb is preferably made to engage the inner face of the diaphragm and is held firmly against the same through the action of the spring bar 33 whereby the lamp and the socket are rigidly held centrally of the container.
50. While I have shown the tubular member 25 formed separately from the transverse wall 23 it may, if desired, be formed integral therewith and the opening in the top of the container made large enough to permit the wick to be inserted downwardly upon said tubular member. Furthermore, it will be understood that the invention is not limited to the details of construction shown as different modifications thereof 55 may be devised within the scope of the appended claims.

I claim as my invention:

1. In a device of the class described, a container having a liquid holding chamber 65 provided with an extended tube-like por-

tion open at its upper end and arranged to receive an article having normally invisible markings adapted to be rendered distinct upon the application of moisture thereto, and means within the chamber 70 adapted to vaporize the liquid to permit it to pass upwardly through said opening.

2. In a device of the class described, a container having a supply of liquid and provided with an apertured portion for 75 receiving an article having normally invisible markings adapted to be rendered distinct upon the application of moisture thereto, said article being adapted to substantially close the aperture and an illuminating element within the container adapted to both vaporize the liquid and illuminate the article.

3. In a device of the class described, a container having a liquid holding chamber 85 provided with an apertured portion for receiving an article having normally invisible markings adapted to be rendered distinct upon the application of moisture thereto, a wick within the chamber, and heating 90 means for vaporizing the liquid absorbed by the wick, the vapor being adapted to pass upwardly through said apertured portion and to be deposited upon said article.

4. In a device of the class described, a 95 container for holding a supply of liquid having an upstanding portion provided with an opening over which an article is adapted to be disposed having normally invisible markings adapted to be rendered 100 distinct upon the application of moisture thereto, a wick projecting into the container and adapted to extend into the liquid, and a heating element within the wick for vaporizing the liquid absorbed thereby.

5. In a device of the class described, a container for holding a supply of liquid having an upstanding portion provided with an opening over which an article is adapted to be disposed having normally invisible markings adapted to be rendered 110 distinct upon the application of moisture thereto, a hollow wick projecting into the container with its lower end extended into the liquid, an illuminating element disposed within the wick for vaporizing the liquid absorbed thereby and for illuminating the markings and a diaphragm for restricting the light rays projected upon the article.

6. In a device of the class described, a container for holding a supply of liquid having an upstanding portion provided with an opening over which a transparent article is adapted to be disposed having normally invisible markings rendered visible upon the application of moisture thereto, a wick within the container projecting into the liquid, an illuminating element within the container adapted to both illuminate said article and to vaporize the liquid absorbed by the wick,

and means within the container for controlling the light rays projected upon said article.

7. In a device of the class described, a container for holding a supply of liquid having an upstanding portion provided with an opening over which an article is adapted to be disposed having normally invisible markings rendered distinct upon the application of moisture thereto, a hollow wick projecting into the container with its lower end disposed within the liquid, a tubular member within the wick for supporting the same, and a heating element within the tubular member adapted to heat the latter to vaporize the liquid absorbed by the wick.

8. In a device of the class described, a container for holding a supply of liquid having an upstanding portion provided with an opening over which an article is adapted to be disposed having normally invisible markings rendered distinct upon the application of moisture thereto, a hollow wick projecting into the container with its lower end disposed within the liquid, a tubular member within the wick for supporting the same, an electric lamp within the tubular member adapted to both heat the latter to vaporize the liquid absorbed by the wick and to illuminate the markings of said article.

9. In a device of the class described, a container having an opening over which an article is adapted to be disposed having normally invisible markings rendered distinct upon the application of moisture thereto, a transverse wall adjacent the bottom of the container having an opening therethrough, an upstanding tubular member supported by said wall, a wick associated with the tubular member and adapted to extend into a supply of liquid carried by the container, and an electric lamp and socket therefor disposed within the container and adapted to be removed through the bottom thereof, the lamp being arranged to project into the tubular member and to vaporize the liquid absorbed by the wick.

10. In a device of the class described, a container having an opening over which an article is adapted to be disposed having normally invisible markings rendered distinct upon the application of moisture thereto, a transverse wall spaced above the bottom of

the container, a tubular member projecting upwardly into the container from said wall and forming with the latter a liquid tight joint, a wick surrounding the tubular member and having its lower end disposed within a supply of liquid carried by the container, an electric lamp and socket, the former being disposed within the tubular member and the latter within the bottom of the container, spaced lugs upon the inner wall of the container adjacent the bottom thereof, and a supporting member for the lamp and socket, the opposite ends of which are adapted to rest upon said lugs.

11. In a device of the class described, a container having an opening over which an article is adapted to be disposed having normally invisible markings rendered distinct upon the application of moisture thereto, a transverse wall spaced above the bottom of the container and having an opening therethrough, a tubular member projecting upwardly into the container and having an annular flange disposed upon one side of said wall, means for clamping said flange upon the wall, a wick surrounding the tubular member and having its lower end projecting into a supply of liquid carried by the container, and a heating element disposed within the tubular member.

12. In a device of the class described, a container having a liquid holding chamber provided with an opening at its upper end, the opening being adapted to be substantially closed by an article having a normally invisible marking arranged to be rendered distinct upon the application of moisture thereto, and a heating element within said chamber in spaced relation to the liquid adapted to vaporize the latter.

13. In a device of the class described, a container having a liquid holding chamber from which extends a tube like portion open at its upper end, a member of relatively soft material upon said end arranged to receive an article having a normally invisible mark adapted to be rendered distinct upon the application of moisture thereto, and means within said chamber adapted to vaporize the liquid to permit it to pass upwardly through said opening in contact with said article.

GEORGE B. GALLASCH.
